TELEPHONE ACOUSTIC DATA COUPLER

Darrel S. Jahn, Mountain View, and Errol J. Coyle,
Sunnyvale, Calif., assignors to Info-Max, a corpora-
tion of California

Filed Nov. 10, 1969, Ser. No. 19,994

Term of patent 14 years

Int. Cl. D14—03

U.S. Cl. D26—14

FIG_1

FIG_2

FIG_3

FIG. 4

FIG. 5

FIG. 6

FIG. 1 is a perspective view of a telephone acoustic data coupler embodying our new design;

FIG. 2 is a right side elevation view of the same (the left side elevation view is a mirror image of this right side elevation view);

FIG. 3 is a front elevation view of the same;

FIG. 4 is a top plan view of the same;

FIG. 5 is a bottom plan view of the same; and

FIG. 6 is a rear elevation view of the same.

We claim:

The ornamental design for a telephone acoustic data coupler, substantially as shown and described.
